United States Patent Office

Des. 223,142
Patented Mar. 21, 1972

223,142

JUG OR SIMILAR ARTICLE

Victor Koenigsberg, Franklin Square, N.Y., assignor to
Colgate-Palmolive Company, New York, N.Y.

Original design application Nov. 14, 1969, Ser. No. 20,093,
now Patent No. 219,954, dated Feb. 23, 1971. Divided
and this application May 25, 1970, Ser. No. 23,178

Term of patent 14 years

Int. Cl. D9—01

U.S. Cl. D9—45

FIG. 2

FIG. 4

FIG. 1

FIG. 5
FIG. 6

FIG. 3

FIG. 8

FIG. 10

FIG. 7

FIG. 11

FIG. 9

FIG. 1 is a side elevational view of a jug or similar article embodying my new design, the opposite side being a mirror image of the side shown;

FIG. 2 is a top plan view thereof;

FIG. 3 is a bottom plan view thereof;

FIG. 4 is an end elevational view as seen from the left of FIG. 1;

FIG. 5 is an end elevational view as seen from the right of FIG. 1;

FIG. 6 is a cross-sectional view taken on the line 6—6 of FIG. 1, said view being taken in the direction of the arrows and showing the outline of the jug on the horizontal sectional plane passing through said line 6—6;

FIG. 7 is a side elevational view of a modified form of my new design, the opposite side being a mirror image of the side shown;

FIG. 8 is a top plan view thereof;

FIG. 9 is a bottom plan view thereof;

FIG. 10 is an end elevational view as seen from the left of FIG. 7; and

FIG. 11 is an end elevational view as seen from the right of FIG. 7.

This application is a division of my copending application Ser. No. D. 20,093, filed Nov. 14, 1969, now Pat. No. D. 219,954 issued Feb. 23, 1971.

I claim:

The ornamental design for a jug or similar article, as shown and described.
